UNITED STATES PATENT OFFICE.

CALVIN L. DENNIS, OF GLEN RIDGE, NEW JERSEY.

FABRIC-TESTING MACHINE.

Application filed May 11, 1926. Serial No. 108,386.

This invention relates to testing machines.

The principal object of the present invention is the provision of a machine for testing the wear resisting qualities of divers products such as textiles, thread, yarn and others which in being utilized are subjected to wear.

Another object of the present invention is to provide a testing machine adapted to subject a piece of fabric to frictional action, 10 and by registering the extent of such frictional action so that comparative tests as to the wear resisting qualities of different fabrics may be made.

Another object of the invention is the provision in a fabric testing machine of means for subjecting a piece of fabric to frictional action, and means for imparting movement to the portion of the fabric being subjected with respect to the means setting up the 20 frictional or wearing action.

With the foregoing and other objects in view the invention resides in the particular provision, construction and operation of the parts. The nature of the invention and its 25 distinguishing features and advantages will appear when the following specification is read in connection with the accompanying drawings, in which—

Figure 1 is a perspective view of the machine of the present invention.

Fig. 2 is a vertical sectional view illustrating certain features of the machine, the section being taken on the line 2—2 of Fig. 3.

Fig. 3 is a plan view illustrating certain 35 features of the machine.

Fig. 4 is an elevation of the combined clamp and weight used for tensioning.

Fig. 5 is a diagrammatic view illustrating certain features of the means for controlling 40 the operation of the power mechanism.

Fig. 6 is a sectional view of the control device for controlling the operation of the power mechanism.

Generally stated, the machine of the present invention comprises a wearing means, 45 supporting means for supporting a piece of fabric or the like in place with respect to the wearing means, tensioning means for maintaining a portion of the fabric in contact with the wearing means to be subjected to frictional or wearing action, means imparting movement to the portion of the fabric being subjected to the frictional or wearing action, power mechanism for actuating the wearing means, and a registering or indicating means which registers or indicates

the extent of the frictional or wearing action required for wearing through the portion of the fabric being subjected to the frictional or wearing action. It will therefore be obvious that with a machine as characterized, tests may be made to determine the comparative wear resisting qualities of different fabrics. While the machine of the present invention, in the present instance, is described to disclose how a piece of fabric may be tested to determine its wear resisting qualities, it is to be understood that the machine may be used for testing other products such as leather, cordage, thread, 70 yarn, etc.

More specifically stated the machine in the illustrated embodiment consists of and operates in a manner presently to be described. A suitable base 10 is provided to 75 which is secured supports 11 each having a bearing 12 which rotatably supports a shaft 13 which is horizontally disposed. Wearing means is provided and in the present instance is in the form of a roll 14 which 80 is secured to the shaft 13 to rotate therewith, and the said roll has a cylindrical abrasive surface 15. Rising from the base 10 are stationary supports 16 and 17, each of which has a horizontally disposed supporting bar 18. The bar 18 of the support 17 is provided with guide members 19. The supports 16 and 17 are arranged respectively at opposite sides of the roll 14 as shown most clearly in Figs. 2 and 3. The supporting bars 18 serve for supporting a piece 85 of fabric in place with respect to the cylindrical abrasive surface 15, the fabric being designated 20. In order to maintain a portion of the fabric in contact with the surface 15 under a predetermined tension there is provided a tensioning means, which, in the present instance, consists of a clamping device 21 which clamps one end of the piece of fabric 20 and a combined clamp and 90 weight 22 which is suspended from the other end of the piece of fabric. The device 21 comprises a part 23 pivotally mounted as at 24, and a part 25 which is pivotally connected as at 26 to the part 23, the part 25 having a serrated portion 27 which engages a portion of the fabric and clamps it against a portion of the part 23 as shown most clearly in Fig. 2. The combined clamp and weight 22 consists of a part 28 to the lugs 110 29 of which a clamping member 30 is pivotally connected as at 31, the clamping mem-

ber having a serrated portion 32 which engages a portion of the fabric and clamps it against the part 28 as shown most clearly in Fig. 2, there being a weight 33 which is detachably connected to the part 28 by the use of a fastening element 34. In the present instance one weight member 22 is shown, but obviously any number of these members may be used so as to alter the tension on the fabric.

Power mechanism is provided for rotating the roll 14, and in the present instance includes an electric motor 35 mounted on the base 10. Motion is transmitted from the drive shaft of the motor to the shaft 13 by the intervention of a small pulley 36 on the drive shaft of the motor, a large pulley 37 on the shaft 13, and a driving belt 38 which encircles the pulleys 36 and 37. It will now be understood that rotary motion will be imparted to the roll 14 and as a result the surface 15 will set up a wearing action on a portion of the fabric 20.

In order to impart movement to a portion of the fabric with respect to the abrasive surface 15 so that a wearing action on the filling threads as well as the warp threads of the fabric will be set up, there is provided an oscillator 39, the lower end of which is pivotally connected as at 40 to the base, the upper end of which is bifurcated to provide furcations 41 which engage a portion of the fabric 20 as shown most clearly in Fig. 3. The oscillator 39 is oscillated by virtue of motion transmission means arranged between the shaft 13 and said oscillator, said means in the present instance consisting of a worm 42 keyed to the shaft 13, a worm gear 43 keyed to a shaft 44 rotatably mounted in bearings 45 carried respectively by supports 46 secured to and rising from the base 10, a disk 47 on the shaft 44, and a pitman 48 arranged between the disk and the oscillator 39. It will now be apparent that when the motor is operating to rotate the roll 14 the oscillator 39 will also be in operation to impart reciprocating movement to the portion of the fabric in contact with the abrasive surface 15.

In order to cease the operation of the motor when the fabric is worn through as a result of the frictional or wearing action set up, there is provided an electrical controlling device 49 which is electrically connected in series with the windings of the motor 35. The device 49 includes a base construction 50 of insulating material in the bottom of which is arranged contacts 51 each under the influence of a spring 52 to yieldingly hold the contacts 51 normally elevated. A bridge piece 53 is provided and is arranged for movement in guides 54 carried respectively by the sides of the base 50. The bridge piece 53 is pivotally connected

to a button 55 arranged in the top of the base 50, there being a spring 56 which functions to hold the bridge piece 53 normally out of contact with the contacts 51. One of the contacts 51 is connected to one side of the motor 35 and the other contact 51 is connected to one side of the source of electrical energy, the other side of which is connected to the motor as shown most clearly in Fig. 5. The circuit also includes a switch 57 for opening and closing the circuit. It will now be apparent that when a piece of fabric is in place for carrying out the testing operation, the part 23 of the device 21 will be pressing downwardly on the button 55 and as a result the bridge piece 53 will bridge the contacts 51 and the motor will be constantly in operation. When the fabric is worn through as a result of the wearing action of the abrasive surface 15 the tension on the device 21 will be released, and as a result the spring 56 will function to elevate the bridge piece 53 out of contact with the contacts 51 therefore ceasing the operation of the motor 35.

In order to register or indicate the extent of wearing or frictional action required for wearing through the fabric there is provided a device 60 in the form of a register or counter having an arm 61 which is encountered by the head 62 which secures one end of the pitman 48 to the disk 47 in each revolution of the disk. In that way the number of revolutions of a moving part will be registered in the device 60 thus indicating to a person the extent of action required for wearing through a particular piece of fabric. Fabrics having great wear resisting properties will be subjected to a longer wearing action than fabrics having lesser wearing qualities and this will be indicated by figures displayed by the device 60 as will be understood.

It is to be understood that the invention is not restricted to the precise arrangement of parts shown and described, as details of construction may be modified and rearranged without departing from the spirit of the invention, the scope of which is limited only by the terms of the appended claims.

I claim:

1. A fabric testing machine comprising wearing means, fabric supporting means for supporting a piece of fabric in place with respect to the wearing means, tensioning means for maintaining a portion of the piece of fabric in contact with the wearing means to be subjected to the wearing action thereof, means imparting movement to the portion of the piece of fabric being subjected to the wearing action, power mechanism for actuating the wearing means, indicating means responsive to the operation of a moving part of the power mechanism to indicate the extent of wearing action required for

wearing through the portion of the piece of fabric subjected to the wearing action, and means operable when the piece of fabric is worn through for ceasing the operation of the power mechanism.

2. In a fabric testing machine, mechanism for subjecting the fabric to a wearing action, said mechanism including a rotatable wearing means, and means acting on a portion of the fabric and constantly keeping said portion in motion relatively to the wearing means in contact therewith.

3. A fabric testing machine comprising a roll having an abrasive surface, power means for rotating the roll, fixed supports, one at each side of the roll on which the fabric is arranged and supported, a pivotally mounted clamp for gripping one end of the fabric, a weight suspended from the other end of the fabric, said clamp and weight constituting a means for placing the fabric under tension with a portion thereof in contact with the abrasive surface of the roll, said power means including a controlling device for controlling the operation of the power means, said controlling device being under the influence of a part of said clamp until the fabric is worn through under the action of the abrasive surface whereupon said controlling device functions automatically to cease the operation of the power means.

4. In a fabric testing machine, mechanism for subjecting the fabric to a wearing action, said mechanism including a wearing means, means for continuously moving the wearing means and means imparting movement to a portion of the fabric relatively to the wearing means in contact therewith, said last mentioned means including an oscillatory member engageable with the fabric for imparting movement thereto.

5. In a testing machine, a rotatably mounted roll having a cylindrical abrasive surface, an electric motor, a driving means between the roll and the motor by virtue of which said roll is rotated, holding and tensioning means for holding a portion of a piece of material under tension in contact with the abrasive surface so as to be subjected to the wearing action of the abrasive surface as a result of the rotation of the roll, means which coacts with the holding and tensioning means for ceasing the operation of the motor immediately the material is worn through, and an odometer operated by a driven part of said driving means.

6. In a testing machine, a rotatably mounted roll having a cylindrical abrasive

surface, an electric motor, a driving means between the roll and the motor by virtue of which said roll is rotated, holding and tensioning means for holding a portion of a piece of material under tension in contact with the abrasive surface so as to be subjected to the wearing action of the abrasive surface as a result of the rotation of the roll, an oscillator having means for engaging a portion of the material, means connected between the oscillator and a driven part of said driving means for oscillating the oscillator to cause the reciprocatory movement of the portion of the material in contact with said abrasive surface, means which coacts with the holding and tensioning means for ceasing the operation of the motor immediately the material is worn through, and an odometer operated by a driven part of said driving means.

7. In a testing machine, a rotatably mounted abrasive element, an electric circuit, an electric motor in said circuit, a switch in said circuit, a make and break device in said circuit automatically operable to break the circuit, driving means between the abrasive element and the motor for effecting the rotation of the abrasive element, holding and tensioning means for holding a portion of a piece of material in contact with the abrasive element so as to be subjected to the wearing action thereof in the rotation of said abrasive element, said holding and tensioning means including a movable part which actuates the make and break device to close the circuit when the holding and tensioning means is functioning to tension said piece of fabric, said movable part being free to move when the material is worn through to permit the make and break device to operate to break the circuit to cease the operation of the motor.

8. In a testing machine, a rotatably mounted roll having a cylindrical abrasive surface, power means for rotating said roll, holding and tensioning means for holding material to be tested under tension in contact with the abrasive surface so as to be subjected to the wearing action of the abrasive surface as a result of the rotation of the roll, means operated by the power means for imparting movement to the material and constantly keeping said material in motion relatively to the abrasive surface in contact therewith, and means which coacts with the holding and tensioning means for ceasing the operation of the power means immediately the material is worn through.
